UNITED STATES PATENT OFFICE.

CHARLES E. LURCOTT, OF PHILADELPHIA, PENNSYLVANIA, ASSIGNOR TO PHILADELPHIA LAST & PATTERN CO., OF PHILADELPHIA, PENNSYLVANIA, A CORPORATION OF PENNSYLVANIA.

LAST.

Application filed May 27, 1926. Serial No. 111,930

This invention relates to improvements in lasts and particularly a last construction whereby the material forming the last is reinforced and strengthened against splitting or breaking in use and in which means is constructed and arranged whereby in use blows or impacts thereon have a tendency to draw and hold the material of which the last is made together and prevent its separation particularly along the grain thereof.

The improvement relates particularly to the heel part or portion of the last and includes a driven reinforcing element having relatively steep threads inserted in this part 15 of the last from the top and extending down through the comb or narrow portion thereof and into the wider or thicker part, being preferably located near the rear edge, whereby the material of this part of the last is 20 securely held together and prevented from splitting or cracking. This reinforcing element is also provided with a comparatively enlarged head so that in use blows or impacts are received by the element on its 25 head, resulting in a tendency to turn the element and thus tighten the material of which the last is made.

To the accomplishment of the foregoing and such other objects as may hereinafter appear, this invention consists in the construction, combination and arrangement of parts hereinafter described and then sought to be defined in the appended claims, reference being had to the accompanying drawings forming a part hereof and which show, merely for the purpose of illustrative disclosure, a preferred embodiment of my invention, it being expressly understood, however, that various changes may be made in practice within the scope of the claims without digressing from my inventive idea.

In the drawings—

Figure 1 is a longitudinal section through a shoe last showing my invention.

Figure 2 is a rear end elevation of the last showing the reinforcement element in phantom and dotted lines.

Figure 3 is a top plan view of part of the heel portion of the last showing the parts forming the subject matter of this invention.

In the drawings, the numeral 1 designates a last as a whole and 2 the heel portion or part of the last, the illustration being of a hinged last. The last, of course, conforms

to the shape of the foot and the heel portion or part 2 has the comb or narrow portion 3. This comb or narrow portion 3 is usually of considerable length and height and is subject to breaking particularly horizontally, especially when the last is made of the usual material, that is wood, because the grain usually runs horizontally and in the use of the last and particularly in the heel operation it is subjected to strains, stresses and impacts of considerable force which result frequently in splitting and breaking of the last itself. The upper part of this last is provided with the layered leather portion 4 through which and into the last itself extends a jack pin thimble 5 which is adapted to receive the jack pin (not shown) for holding the last during operation.

Means for strengthening and reinforcing this portion or part of the last is shown separately in Figure 2 and comprises an elongated screw member 6 having a tapered or sharpened non-threaded point 7 whereby it may be driven. This screw member 6 is threaded on a relatively steep pitch and with a comparatively wide thread and has a flat head or top 9 with a smooth or non-threaded portion 10 between the head or top 9 and the threaded portion 8. It is adapted to be driven through the leather top portion 4 of the heel part or portion of the last and into the material of the last itself preferably to the rear of the jack pin thimble 5. When this element is in position the flat head, which is of substantial area, is exposed on top of the heel portion or part of the last so as to receive blows or impacts during the operations in which the last is used.

The driving of this screw or reinforcing element into position and any blow or impact or pressure on the head thereof causes it to turn or tend to turn, binding and drawing the wood of the heel portion or part of the last together and thereby preventing the same from splitting under impact and pressure when in use, and also affording a direct reinforcement of this part of the last structure. The screw parallels the jack pin thimble and is of sufficient length to extend through the comb or thin portion of the heel part of the last, as shown, and down into the wider or thick part of the heel portion of the last. It is arranged quite

near the rear edge of the heel portion of this last and thereby prevents the starting of the splitting or cracking of the material forming the last at the rear edge of the same.

In the construction illustrated, a transverse rod or rivet 11 is passed through the comb or thin part of the heel portion and secured in position, preferably between the jack pin thimble and the screw-threaded member 8. This construction operates to brace this thin part of the heel portion of the last in each and every direction and in operation the screw-threaded member or reinforcing element 6 will have a continuous tendency to draw the material of the heel portion of the last together and also to prevent the separation of the same as in splitting or cracking. It is to be noted that the unthreaded portion of the screw member is of sufficient length to extend through the leather part of the heel portion of the last so that the screw thread extends into the wood of the heel portion of the last only.

In addition the head or top of the screw, being flat and of substantial extent, operates as protection for the part of the last in which it is positioned and receives and distributes the impact from the blows in operation, and transmits this pressure to the screw itself, resulting in a turning movement or a tendency to turn, thereby tightening up the structure.

It is to be understood that the last itself is of the standard form used in connection with shoe machinery and has the usual metallic heel plate 12. It is customary to drive the heel on the shoe at a single blow under enormous pressure because the heel as a whole is fastened on by the one blow driving all of the nails home, which subjects the last to tremendous pressure, stress and strains and this invention prevents the splitting, cracking and breaking of the last due to these factors.

What I claim is:

1. In combination, a shoe last having a heel part or portion provided with a comb or narrow portion, a jack pin thimble extending into said comb or narrow portion from the top thereof and means for reinforcing and drawing the material of the comb or narrow portion of the last together, said means being located in the rear of the jack pin thimble and extending into the material of the heel part or portion of the last for a considerable distance, said means including an elongated element screw threaded on a steep pitch and having an exposed head so that blows in operation result in a turning movement of the element in the material of

the last so as to bind the grain of the material thereto.

2. In combination, a shoe last having a heel part or portion provided with a comb or narrow portion, a jack pin thimble extending into said comb or narrow portion from the top thereof and means for reinforcing and drawing the material of the comb or narrow portion of the last together, said means being located in the rear of the jack pin thimble and extending into the material of the heel part or portion of the last for a considerable distance, said means including an elongated element screw threaded on a steep pitch and having an exposed head so that blows in operation result in a turning movement thereof in the material of the last so as to bind the grain of the material thereto, said exposed head being flat and of substantial area and adapted to receive blows or impacts during operation and to protect the top of the comb or narrow portion of the heel and also to transmit these blows to the screw-threaded portion of said element.

3. In combination with the heel part or portion of a shoe last, a reinforcing element positioned in the comb or narrow part thereof, said reinforcing element being provided with a driving point, a portion of substantial length threaded on a relatively steep pitch and a flat head of relatively substantial area exposed on top of the heel part or portion of the last to receive blows or impacts in operation, whereby the element has a tendency to turn and thus draw or bind the material of the last together to prevent cracking or splitting thereof.

4. In combination with the heel part or portion of a shoe last, a reinforcing element positioned in the comb or narrow part thereof, said reinforcing element being provided with a driving point, a portion of substantial length threaded on a relatively steep pitch and a flat head of relatively substantial area exposed on top of the heel part or portion of the last to receive blows or impacts in operation, whereby the element has a tendency to turn and thus draw or bind the material of the last together to prevent cracking or splitting thereof, said reinforcing element being located near the rear edge of the heel part or portion of the last and extending through the comb or narrow part thereof into the thicker portion of the last near the bottom thereof.

In testimony that I claim the foregoing, I have hereunto set my hand this 31st day of March, 1926.

CHARLES E. LURCOTT.
